UNITED STATES PATENT OFFICE.

ROSARIO CASTROGIOVANNI, OF BROOKLYN, NEW YORK.

SHOEMAKER'S REPAIR FORM.

Application filed October 26, 1921. Serial No. 510,490.

To all whom it may concern:

Be it known that ROSARIO CASTROGIOVANNI, a citizen of the United States, residing at Brooklyn, in the county of Kings and 5 State of New York, have invented certain new and useful Improvements in Shoemakers' Repair Forms, of which the following is a specification, reference being had therein to the accompanying drawing.

10 My invention relates to improvements in shoemakers' forms such as are used by cobblers for resoling and repairing shoes, and more particularly has reference to the configuration or shape of the same by which 15 the form is more readily adapted for use and fits into the shoe better than the usual curved form heretofore employed, thus insuring among other advantages, the turning of the nails when driven through the 20 sole.

In the accompanying drawings, I have illustrated in Fig. 1, in side elevation, a suitable form adapted for use upon men's and boys' shoes. Fig. 2 is a plan view looking 25 upwardly at the same, and Fig. 3 is a cross-section on the line 3—3 of Fig. 1. Fig. 4 is a side elevation of a ladies' or misses' form. Fig. 5 is a plan view of the base thereof, and Fig. 6 is a cross-section on the 30 line 6—6 of Fig. 4.

The sole or tread of the form, it will be observed, is substantially straight and flat both transversely and longitudinally and both fore and aft as indicated at 7 and 8 respectively in the men's form, and 9, 10 in the ladies' form. This flat sole surface irrespective of the interior of the shoe, allows the edge or periphery of the form to engage snugly around the inside of the shoe so 40 that the nails when driven through the sole strike the iron form and are turned, securely fastening the sole in position, whereas according to the present practice, these iron forms have habitually been made with 45 curved sole or base portions leaving a space between the inside of the sole and rim of the form, causing the leather sole to spring with each blow of the cobbler's hammer and many times projecting beyond the rim or

edge of the form allowing the nails to project into the shoe, causing considerable difficulty and requiring considerable time of the cobbler reinserting the form to so shift the shoe thereupon as to be able to re-fasten and turn down the nails, frequently resulting in a poorly nailed sole, the nails of which not only tear the socks or stockings of the wearer, but frequently cut the flesh and ruin the hose. Furthermore, the flat surface of the form prevents the point of the nail from being deflected outwardly from the inside of the shoe, sometimes cutting through the upper.

The reinforcing webs such as 11—12, it will also be observed while sufficiently stout to give all necessary strength to the form, are not projected sufficiently to interfere with the insertion of the form into the shoe, the curve of the web or rib sweeping down close to the instep and then forwardly close 70 to the base or sole of the form. Another important advantage in the shape disclosed is the pointed toe 13—14 which insures a support for the nails at the toe to strike, whereas in the more rounded forms now in use, 75 these nails enter the toe of the shoe without being turned, thereby coming loose and opening up the shoe. Of course where a rounded toe shoe is being repaired the point of the form is shifted from side to side 80 therein as the nails are driven, thus insuring the proper support and deflecting base for the nail.

The error heretofore seems to have been that the trade has thought it necessary that 85 the base of the form be rounded to conform to the conventional inside form of the sole of the shoe, whereas it has been found that by flattening the form and pointing it as shown, the shoe can be readily shifted thereupon and the edge of the form can be projected entirely within the interior corners of the shoe to meet the nails driven through the sole, thus serving a decided advantage 90 not only in the accomplishment of the work, but in the saving of time in so doing.

Of course it will be understood that various modifications may be made in the con-

struction and arrangement of parts without departing from the spirit of the invention as claimed.

I claim:

- 5 In a form of the class described, a sole or base portion substantially flat, producing in elevation substantially a straight line both transversely and longitudinally, and a heel portion therefor also substantially flat,

and having a pointed toe portion, a reinforcing web of slight projection from the toe to the shank turning sharply substantially at the instep thereof and in combination side webs extending upwardly from said base to a point beyond the ankle. 10

In testimony whereof I hereunto affix my signature.

ROSARIO CASTROGIOVANNI.
